CLAIM

The ornamental design for a shoe, as shown and described.

DESCRIPTION

FIG. 1 is a first side view of a shoe showing my design;

FIG. 2 is a second side view thereof;

FIG. 3 is a top view thereof;

FIG. 4 is a front view thereof;

FIG. 5 is a rear view thereof;

FIG. 6 is a front perspective view thereof;

FIG. 7 is a first side rear perspective view thereof; and,

FIG. 8 is a second side rear perspective view thereof.

The even-length broken lines are directed to environment, represent unclaimed subject matter, and form no part of the claimed design.

1 Claim, 8 Drawing Sheets
